US0D1006012S

(12) **United States Design Patent** (10) Patent No.: **US D1,006,012 S**
(45) Date of Patent: ** Nov. 28, 2023

(54) **COMPUTER**

(71) Applicant: **Siemens Aktiengesellschaft**, Munich (DE)

(72) Inventors: **Zhan Bo Ren**, Chengdu (CN); **Andreas Morlock**, Pfinztal (DE); **Xue Kang Li**, Chengdu (CN); **Shi Kong Lin**, Chengdu (CN); **Ting Li Lan**, Chengdu (CN)

(73) Assignee: **SIEMENS AKTIENGESELLSCHAFT**, Munich (DE)

(**) Term: **15 Years**

(21) Appl. No.: **29/771,679**

(22) Filed: **Feb. 24, 2021**

(30) **Foreign Application Priority Data**

(57) **CLAIM**

The ornamental design for a computer, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof; and,

FIG. 7 is a front, top and right-side perspective view thereof. The broken lines show portions of the computer which form no part of the claimed design.

1 Claim, 7 Drawing Sheets
